DOOR LIFT MECHANISM

Jerome J. Oleksiw, Berwick, Pa., assignor to
American Car and Foundry Company, New
York, N. Y., a corporation of New Jersey

Application June 10, 1939, Serial No. 278,439

8 Claims. (Cl. 16—99)

This invention relates to lift mechanism in general and in particular to such mechanism when applied to sliding doors intended for rail-way service.

5 A large number of distinct types of door lift mechanisms are at present in use but in practically every case these mechanisms are hard to operate due to sliding or rubbing contact between the lift parts. It is an object, therefore, 10 of the present invention to provide a door lift mechanism with the parts so arranged as to reduce the frictional drag to a minimum during the lifting of the door.

15 A further object of the invention is the provision of a door lift mechanism having the main door supporting rollers carried directly by the door and in spaced relation to the supporting track at all times.

20 A still further object of the invention is the provision of a door lift mechanism in which the main door supporting rollers are carried directly by the door for rotational movement only, thereby permitting of the proper and permanent alignment of the bearings.

25 These and other objects of the invention will be apparent to persons skilled in the art from a study of the following description and accompanying drawing in which:

30 Figure 1 is a partial side view of the improved mechanism with parts broken away to better disclose the construction;

Fig. 2 is a transverse sectional view through the lower portion of the door;

35 Fig. 3 is a side view similar to Figure 1 but showing the parts in door lifted position, and

Fig. 4 is a sectional view taken substantially on line 4—4 of Fig. 3.

40 Referring now to the drawing in detail, it will be seen that the front and rear door stiles 2 are connected together adjacent their lower ends by inverted box section bottom rail 4 which is also connected to the door panel 6. The bottom rail, as previously mentioned, is of general inverted box section having sides 8 connected together 45 at the top by web or cover 10 and formed at the bottom with inner and outer flanges 12 and 14 respectively adapted to overlap the supporting track T. Normally, the edges of the bottom rail rest upon the track as shown in Figure 1 and 50 prevent any sliding movement of the door upon the track.

55 Main door supporting rollers 16 are carried within the bottom rail adjacent each end thereof and are mounted upon axles 18 supported by the sides of the bottom rail, either by being

projected therethrough or resting in bearing lugs attached to the sides. In this manner it will be seen that the main door supporting rollers may be carefully aligned in the bottom rail and the axles properly located so as to reduce the 5 friction to a minimum and maintain the bearings in perfect alignment. Since the main supporting rollers may have only rotational movement and since their connection with the door is more or less permanent, it is obvious that if 10 desired roller or ball bearings may be used between the supporting roller and its axle. In order to lift the door, rollers 20 are provided and rotatably carried by an axle 22 extending into side pieces 24 constituting what may be termed 15 a cage for the lift rollers. The side arms of the cage for the forward lift rollers are connected by pin 26 to casting or forging 28 pinned or otherwise non-rotatably connected to shaft 30 20 journaled in the bottom rail and extending upwardly for connection with a handle 32. The casting or forging 28 is formed with spaced arms, between which is positioned one end of connecting bar 36 and through which the pin 26 extends to connect the bar to the casting. The 25 opposite end of the connecting bar is secured by any suitable means, such as rivets 38, to the spaced arms of the rear lift roller cage. The door operating handle is preferably formed integral with the shaft 30 and is provided with inwardly extending lugs 40 and 42, forming a hand grip portion which will prevent slippage of the operator's hand while at the same time protecting the hand from injury by contact with the door. It will be obvious that the lift rollers may 35 be journaled on their axles or the axles may be journaled in the cage sides, in which case it would be more economical to form the axles directly on the rollers.

40 Normally, the door is in position as shown in Figure 1, in which case the door rests directly on the track and the lift rollers 20 do not support any portion of the load. In fact, it will be seen from the angular relation of the parts and the fact that the handle may rotate that it would 45 be impossible for the rollers to assume any load, therefore, the bearings cannot be injured during transit. When it is desired to lift the door it is only necessary to rotate the operating handle downwardly to approximately 45°, forcing the 50 cages toward the side edges of the door, thus causing the lift rollers 20 to roll along the track and along and over the surface of the main supporting rollers 16. Since the main load is carried by the lift rollers and supporting rollers, it will be 55

seen that there is no sliding friction between these parts and, therefore, the frictional drag has been reduced to a minimum. When it is desired to return the door to its normal position, it is only necessary for the operator to release the handle, for the axes of the lift rollers can never be brought beneath the axes of the main rollers and thus there is always a slide component tending to kick the lift rollers from beneath the main rollers which will, of course, return the operating mechanism to its normal position shown in Figure 1. It should be noted that the force necessary to retain the parts in the position shown in Fig. 3 may be rather nicely regulated by limiting the amount of movement permitted one of the cage members, such as the forward one, by use of a stop 50, the thickness of which may be preselected.

While the invention has been described more or less in detail, it is obvious that various modifications and rearrangements of parts other than those shown and referred to may be made by persons skilled in the art and all such modifications and rearrangements of parts are contemplated as will fall within the scope of the appended claims which define my invention.

What is claimed is:

1. In a lift device for sliding doors having a bottom portion normally resting on a supporting track, the combination of main door supporting rollers journaled on said door with their peripheries held in spaced relation to said track at all times, and door lift rollers shiftable into the space between and into direct contact with said main rollers and track to lift the door.
2. In a lift device for sliding doors having a bottom portion normally resting on a supporting track, the combination of main door supporting rollers journaled on said door with their peripheries held in spaced relation to said track at all times, and door lift rollers shiftable into the space between said main rollers and track to lift the door, said main rollers rolling upon the door lift rollers during sliding of the door.
3. In a lift device for sliding doors having a bottom portion normally resting on a supporting track, the combination of main door supporting rollers journaled on said door with their peripheries held in spaced relation to said track at all times, door lift rollers shiftable into the space between and into direct contact with said main rollers and track to lift the door, and means connected to said lift rollers to force the same into said space and retain the same there-in during sliding of the door.
4. In a lift device for sliding doors having a bottom portion normally resting on a supporting track, the combination of main door supporting rollers journaled on said door with their peripheries held in spaced relation to said track at

all times, an operating handle, cages connected to said handle, and door lift rollers journaled in said cages, said operating handle shifting the cages to force said door lift rollers into the space between and into direct contact with the main supporting rollers and track for joint rotary motion during sliding of the door.

5. In a lift device for doors slidable along a supporting track and having a bottom rail, a main anti-friction door supporting device mounted in said bottom rail with its lower-most portion spaced from the track, and an anti-friction door lift device shiftable into the space between said first named device and track to lift the door vertically relative to said track, said 15 anti-friction devices together supporting the door in lifted position and rotating in unison during sliding of the door.

6. In a lift device for doors slidable along a supporting track and having a bottom rail, a main 20 anti-friction door supporting device mounted in said bottom rail with its lower-most portion spaced from the track, and an anti-friction door lift device shiftable into the space between said first named device and track to lift the door 25 vertically relative to said track, said second named device rolling upon said track and first named device during shifting of the device relative to the door and also during sliding of the door.

7. In a lift device for doors slidable along a 30 supporting track and having a bottom rail, a main anti-friction door supporting device mounted in said bottom rail with its lower-most portion spaced from the track, a cage carried within said bottom rail, means to shift said cage within said rail, and an anti-friction door lift device mounted in said cage and rolling on said first named device and into the space between said first named device and track during shifting of the cage to lift the door vertically relative to said track, said door lift device also rolling upon said main anti-friction door supporting device and track during sliding of the door.

8. In a lift device for doors slidable along a supporting track and having a bottom rail, main 45 anti-friction door supporting devices mounted in said bottom rail adjacent each end thereof and with their lower-most portions spaced from the track, an operating handle carried by the rail, cages adjacent each anti-friction device and 50 connected to said handle and movable therewith, and an anti-friction door lift device mounted in each cage, said last named device being movable with said cage and rolling into the space between and in contact with the first named device and track to lift the door vertically relative to the track, said devices rolling upon each other to anti-frictionally support the door in lifted position during sliding movement of the door.
